DRAGLINE RIPPER

Gus Uotila, Fairbanks, Territory of Alaska, and
 John W. Sandusky, Seattle, Wash.; said Uotila
 assignor to said Sandusky

Application June 12, 1947, Serial No. 754,198

2 Claims. (Cl. 262—8)

1

This invention relates to new and useful improvements in dragline rippers.

An object of the invention is to provide a simple, strong, durable mechanism which will quickly and efficiently loosen bedrock that is too securely embedded to be removed by the ordinary dragline buckets, scrapers, or other standard excavating equipment.

The development of this invention arose from the necessity to establish bedrock drains in connection with placer mining. This requires a tool that will loosen bedrock so that the regular excavating equipment could remove the loosened bedrock thus forming a gravity drain ditch below the natural upper surface of the bedrock.

Until drainage is established, the cuts are usually wet and full of loose gravel, making drilling and blasting impractical. So with the regular excavating equipment, it is attempted to cut sufficient bedrock to establish the drain, with the result that great damage is suffered by the regular excavating equipment which is not rugged enough and is not designed for such work, much time is lost and inadequate drainage results.

When the invention herein is employed or to be used, the regular excavating equipment is used until bedrock is reached, after which it is replaced by the device of this invention which is used until the bedrock has been torn up sufficiently to be handled with the standard excavation equipment.

It is another object of this invention to provide a device which is adapted to be manipulated by means of two cables and to be dragged along the bedrock to rip the surface thereof, which is achieved by means of its extremely heavy weight and strong ripping teeth.

It is a further object to provide means whereby the slope of the ripper frame and solidly connected teeth may be altered by a front connected cable while in motion to vary the tooth angle at will.

Still another object is to provide simple cable means to lift the front of the ripper at will to clear the front tooth from the loose rock and cause the device to slide on the two rear teeth's bottoms. In this position the device acts as a scraper, moving the loosened rock so it will not interfere with the ripping action of the teeth on the next trip.

Further and more specific objects, features and advantages will more clearly appear from the detailed specification set forth hereinafter especially when considered in connection with the accompanying drawings which illustrate a present

2

preferred form which the invention may assume and which form part of the specification.

In brief and general terms, the invention comprises a heavy ripper frame and teeth which in the small experimental model weighed four tons, and required up to twenty tons to drag it through bedrock by means of side connections, through the medium of an overhead cable, the slope of the frame and teeth which are rigidly connected can be altered at will.

The frame is provided with three strongly embedded or fastened heavy teeth, two of which are disposed to the rear of the center of gravity and on opposite sides of the frame. Between these rear teeth is a large opening extending from top to bottom of the frame and back of this opening is a dependent scraper edge which may come into play when the front of the frame is elevated sufficiently whereby the surface material can be scraped up into and through the opening and during which the spaced rear side teeth help to confine and direct the movement through the opening of the material thus loosened.

The device is controlled like a dragline bucket. Suspended and cast into position with the hoist line and pulled to the machine with the drag cable. The teeth are located to put a minimum strain on the hoist line; however, if the digging is tough, the load line can be tightened, thus putting the maximum weight on the two rear teeth. If they then do not start to rip, the front end can be raised until the desired digging angle of the rear teeth is attained.

The present preferred form which the invention may assume is illustrated in the drawings of which—

Fig. 1 is plan view of the ripper;

Fig. 2 is a vertical longitudinal section taken on the line 2—2 of Fig. 1;

Fig. 3 is a vertical transverse section taken on the line 3—3 of Fig. 1;

Fig. 4 is a side elevation of one form of tooth;

Fig. 5 is an end elevation thereof;

Fig. 6 is a side elevation of another form of tooth and fastening means therefor; and

Fig. 7 is an end elevation of the tooth shown in Fig. 6.

As shown in the drawings, the invention in the form illustrated, comprises a heavy flat rectangular frame 10 which is of solid cast steel and may weigh, even in the small sizes, as much as several tons. In the form shown the ripper frame is provided with a plurality of teeth sockets 11, preferably tapered, into which teeth 12 having similarly tapered upper ends are wedged and

welded and are provided also with suitably shaped lower ends for the purpose of ripping open the bed-rock surface. As shown in Figs. 6 and 7, the teeth may also be fastened in place by a pin 13 passing through a hole in the upper end of the teeth and resting on the top of the frame. The pin 13 may be welded in place. Preferably there is one of these teeth toward the front of the frame in the middle thereof and two at the rear spaced apart along the sides of the frame. Between the spaced rear teeth is formed a large opening 14 extending through the frame and around the bottom of this opening the walls are tapered upward and toward the opening as shown at 15 in Fig. 2. This formation results at the rear of the opening 14 of a wedged or triangular rib 16 to be used for a purpose hereafter mentioned. The rear teeth also are quite flat and long and as disposed act as partial walls along the sides of the opening 14.

The forward end of the device is drawn to a somewhat pointed formation 17 and here an eye bolt or device 18 is connected and to which a hoist line cable may be connected. The front sides of the frame 10 are cut away to form recesses 19 and a shaft 20 extends across through suitable openings in the frame and across these recesses to receive pear links or shackles such as 21 connected to suitable dragchains or cable connections 22. By removing key pins 23 from the shaft 20 it can be longitudinally withdrawn to permit removal of the shackles 21 when desired, if they are not otherwise removable.

In the operation of the device, the frame is operated with two cables the same as a standard dragline bucket and can be cast into position by the intermediary of the load-line connection to shackle 18. Then the frame is dragged along the surface through connections 22. Depending upon the nature and toughness of the bedrock the front end may be tilted up by proper tension on the shackle 18 whereby the slope of the front face of the teeth 12 may be varied as desired. If the surface is very hard the teeth may thus be lifted to raise the front teeth out of the rock contact whereby the whole load is on the rear teeth. It is also possible to tilt the frame still more and lift all the teeth points from contact whereupon the triangular scraper rib 16 comes into play scraping the already ripped rock out of the cut so that the operation can be continued. The material thus scraped loose will pile up in front of the rib 16 and pass up and through the opening 14 and out of the same to be picked up by any suitable device to follow. The side teeth at the rear will act as

baffles to guide and direct the material up through the opening and prevent it from passing out laterally. The sloping shape of the frame around the bottom of the opening 14 will assist in the direction of the material.

While the invention has been described in detail and with respect to a present preferred form which it may assume, it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

What I claim as my invention, is:

1. A dragline ripper which comprises a heavy frame, large, strong teeth dependent therefrom, to be dragged through bedrock, a transverse scraper rib along the bottom of the frame and along the rear edge thereof, said frame having an opening therethrough immediately in front of the rib, and a pair of said teeth, disposed at the rear of the frame on opposite sides and adjacent said opening.

2. A dragline ripper which comprises a heavy frame, large, strong teeth dependent therefrom, to be dragged through bedrock, a transverse scraper rib along the bottom of the frame and along the rear edge thereof, said frame having an opening therethrough immediately in front of the rib, the walls of the frame at the bottom around said opening being sloped up toward a pair of said teeth, disposed at the rear of the frame on opposite sides and adjacent said opening, and means on the frame whereby the front end may be lifted to vary the pitch of the teeth and to bring said rib into scraping action.

GUS UOTILA.
JOHN W. SANDUSKY.
